(57) **CLAIM**

The ornamental design for a camera, as shown and described.

DESCRIPTION

FIG. 1 is a perspective view of a camera showing my new design;

FIG. 2 is a perspective view thereof, the barrier being in an opened state and the lens extended;

FIG. 3 is a top plan view thereof;

FIG. 4 is a front elevational view thereof;

FIG. 5 is a bottom plan view thereof;

FIG. 6 is a left side elevational view thereof;

FIG. 7 is a right side elevational view thereof;

FIG. 8 is a rear elevational view thereof;

FIG. 9 is a top plan view thereof, the barrier being in an opened state and the lens extended;

FIG. 10 is a front elevational view thereof, the barrier being in an opened state and the lens extended; and,

FIG. 11 is a right side elevational view thereof, the barrier being in an opened state and the lens extended.

The portions of the camera in broken lines are shown for illustrative purposes only and form no part of the claimed design.

The claimed lens barrier and S-like curved line are both structural elements of the camera.
